UNITED STATES PATENT OFFICE.

CHARLES NEUBERT, JR., OF BALTIMORE, MARYLAND.

CAN CLOSURE AND PROCESS FOR APPLYING SAME.

Application filed September 20, 1923. Serial No. 663,811.

To all whom it may concern:

Be it known that I, CHARLES NEUBERT, Jr., a citizen of the United States, residing at Baltimore, in the State of Maryland, have invented certain new and useful Improvements in Can Closures and Processes for Applying Same; and I do hereby declare the following to be a full, clear, and exact description of the invention, such as will enable others skilled in the art to which it appertains to make and use the same.

My invention relates to can closures and processes for applying same.

Among the objects of my invention are:

To produce a can closure which can be readily applied to a can after the can is charged with any desired substance and then by the application of my improved process, I crimp the closure in such a manner that displacement thereof during transportation will be prevented. I preferably produce the crimping of the closure in such locations and of such shapes that said closure may be removed from the can without destruction of either the closure or can, so that said closure may be removed from and replaced in the can a plurality of times by the ultimate consumer.

These and further objects of my invention will be set forth in the following specification, reference being had to the accompanying drawings, and the novel means and process involved in my invention will be definitely pointed out in the claims.

In the drawings:

Figure 1 is a plan view of the top of the can showing my improved closure applied thereto.

Fig. 2 is a section along the line 2—2 in Fig. 1 looking in the direction of the arrows.

In the drawings:

5 represents a can which is formed in any approved manner and has a top provided with the inturned flange 6.

15 The closure 7 is formed in any approved manner and is provided with a flange 8 which fits snugly within the flange 6. The closure 7 is provided with a lip 9 which normally rests slightly above the top of the can 5 so that a screw driver or other suitable tool may be placed between said top and said lip for the purpose of removing the closure 7.

In practicing my improved process, I 55 first fill the can 5 with the desired substance and then introduce the flange 8 within the

flange 6 and press the closure towards the top of said can until it occupies the position shown in Fig. 2.

It being understood that the flange 8 is 60 merely a smooth cylindrical flange slightly longer than the flange 6 and which fits snugly within the latter, danger exists that the closure 7 will be inadvertently displaced from the can 5 when the latter is used for 65 transporting liquid or semi-liquid substances. This difficulty has existed to such an extent that it has been the custom heretofore to apply solder to the lip 9 and the top of the can in order to secure the closure in 70 place.

The object of my improved process is to obviate the necessity for applying solder to the lip 9 and top of the can 5.

After the closure 7 is placed in position, as 75 just explained, I then produce any desired plurality of indentations 10 within the lower end of the flange 8 in order to form projections extending past the lower edge of the flange 6.

80 The indentations 10 are so shaped that the upper surface of the projections on the outside of the flange 8 will be disposed at an obtuse angle to the upper part of the flange 8 in order to insure that when the requisite degree of force is applied to the lip 9, the angular upper surface of said projections will slightly force the adjacent portions of the flange 6 outwardly in order to 85 permit said projections to pass upwardly 90 within the flange 6 to permit of the removal of the closure 7.

95 The bottom surfaces of the indentations 10 are curved to permit of the insertion of the closure after its removal.

When the closure 7 is forced upwardly, as just described, the flange 6 springs outwardly adjacent the projections formed by the indentations 10 and thus causes the metal in the other parts of the flange 6 to impinge with greater force upon the flange 8 and deform the same slightly in order to provide a sufficient yielding of the flange 6 near said projections in order to permit the removal of the closure 7 as before stated.

105 It is to be noted that my improved process comprehends the following steps:—First, the filling of the can; second, the placing of the closure within the can; and third, the forming of indentations within a portion of the closure which indentations produce projections on the surface of the clo-

sure, which projections are so related to the body of the can as to hold said closure in place with sufficient force to withstand any shocks that would occur during transportation, which projections are so shaped as to cause a sufficient deformation of the adjacent portions of the can body as to permit of the ready removal of the closure.

Thus, my improved closure and process 10 of applying the same broadly differentiate my invention from those closures and cans which are prepared with locking means before the application of the closure to the can.

15 While I have shown one arrangement of projections related to one form of can, it is to be understood that the disclosure is for purposes of illustration only and in nowise to limit the scope of my invention, for 20 changes may be made in the structure of the can and the closure and in the shape of the projections without departing from the spirit of my invention.

I claim:

25 1. The combination with a can having an opening surrounded by a flange, of a closure fitting within said flange and projections formed on said closure below said flange to secure said closure in place, said 30 projections being shaped to permit said projections to displace portions of said flange to permit of the removal of said closure.

2. The combination with a can having a

flat top provided with an opening surrounded by a flange, of a closure fitting 35 within said flange and projections formed on said closure below said flange to secure said closure in place, said projections being shaped to permit said projections to displace portions of said flange to permit of the removal of said closure.

3. The combination with a can having a flat top provided with an opening surrounded by a cylindrical flange, of a closure having a cylindrical portion fitting with said 45 flange and projections formed on said portion below said flange to secure said closure in place, said projections having tops disposed at such angles to said flange that said tops will press the adjacent portions of said 50 flange outwardly to permit the passage of said projections when said closure is being removed.

4. The herein described process of securing materials in cans which consists in forming said cans with an opening surrounded by a flange, placing said materials in said cans, forcing into said flange a closure having a portion closely fitting said flange, and pressing indentations into said portions in 60 order to form projections extending across the edge of said flange to secure said closure in place.

In testimony whereof, I affix my signature.

CHARLES NEUBERT, JR.
